US0D1100918S

(12) **United States Design Patent** (10) Patent No.: **US D1,100,918 S**
Magstadt et al. (45) Date of Patent: ** Nov. 4, 2025

(54) **DISPLAY SCREEN WITH GRAPHICAL USER INTERFACE**

(71) Applicant: **SwineTech, Inc.**, Solon, IA (US)

(72) Inventors: **Adam Magstadt**, Solon, IA (US);
Joseph Palermo, Solon, IA (US);
Matthew Rooda, Solon, IA (US)

(73) Assignee: **SWINETECH, INC.**, Cedar Rapids, IA (US)

(**) Term: **15 Years**

(21) Appl. No.: **29/871,139**

(22) Filed: **Feb. 13, 2023**

(51) LOC (15) Cl. **14-04**

(52) U.S. Cl.

USPC **D14/485**

(57) **CLAIM**

The ornamental design for a display screen with graphical user interface, as shown and described.

DESCRIPTION

The FIGURE is a front view of a display screen with graphical user interface.

The broken lines showing an electronic device illustrate environmental subject matter and form no part of the claimed design. The remaining broken lines showing a display screen and elements of the graphical user interface illustrate portions of the article and form no part of the claimed design.

1 Claim, 1 Drawing Sheet
